Primary Examiner — Cathy Anne MacCormac*(74) Attorney, Agent, or Firm* — Ryan Kromholz & Manion, S.C.(57) **CLAIM**

The ornamental design for a feline play structure, as shown and described.

DESCRIPTION

FIG. 1 is a perspective view of the invention;
 FIG. 2 is a front elevation view;
 FIG. 3 is a rear elevation view;
 FIG. 4 is a right side elevation view;
 FIG. 5 is a left side elevation view;
 FIG. 6 is a top plan view;
 FIG. 7 is a bottom plan view; and,
 FIG. 8 is an enlarged partial detail perspective view of encircled portion 8 as shown on FIG. 1 to show the pattern on the legs.

The dot-dash broken line on FIGS. 1 and 8 encircling a portion of the claimed design form no part of the claimed design.

1 Claim, 2 Drawing Sheets(56)
